US0D1091527S

(12) **United States Design Patent** (10) Patent No.: **US D1,091,527 S**
(45) Date of Patent: ** Sep. 2, 2025

(54) **MOBILE PHONE HOLDER**

(71) Applicant: **Dongguan Weichuang Silicone Rubber Technology Co., Ltd.**,
Dongguan (CN)

(72) Inventor: **Xifeng Yi**, Shenzhen (CN)

(73) Assignee: **Dongguan Weichuang Silicone Rubber Technology Co., Ltd.**,
Dongguan (CN)

(**) Term: **15 Years**

(21) Appl. No.: **29/996,411**

(22) Filed: **Apr. 1, 2025**

(30) **Foreign Application Priority Data**
